UNITED STATES PATENT OFFICE.

GEORGE L. HARRISON, OF EAST CLEVELAND, OHIO.

DESIGN FOR A TABLE.

47,360.

Specification for Design. Patented May 18, 1915.

Application filed February 24, 1914. Serial No. 820,764. Term of patent 14 years.

To all whom it may concern:

Be it known that I, GEORGE L. HARRISON, a citizen of the United States, residing at East Cleveland, in the county of Cuyahoga and State of Ohio, have invented a new, original, and ornamental Design for Tables, of which the following is a specification, reference being had to the accompanying drawing, forming part hereof, wherein—exhibiting my new design; and Fig. 2 is a bottom plan view of a corner of the table.

I claim:—

The ornamental design for a table as shown.

GEORGE L. HARRISON.
